UNITED STATES PATENT OFFICE.

WALTER G. CLARK, OF NEW YORK, N. Y.

METHOD OF MAKING COVERING MATERIAL FOR AIRCRAFT.

1,243,654.

Specification of Letters Patent. Patented Oct. 16, 1917.

Application filed January 20, 1917. Serial No. 143,471.

To all whom it may concern:

Be it known that I, WALTER G. CLARK, a citizen of the United States, and a resident of the borough of Manhattan, city, county, and State of New York, have invented certain new and useful Improvements in Methods of Making Covering Material for Aircraft, of which the following is a specification, accompanied by drawings.

This invention relates to covering material for aeroplanes, balloons or other air craft, or for any other purpose where a thin, light, strong and air tight covering is necessary, and where skin friction is a consideration which makes a smooth surface highly desirable. This application is a continuation in part of my copending application, Serial No. 108,140, filed July 8, 1916, with additional features.

The basis or foundation of the material consists of a web of wire mesh or net, which may be of fine wires, either steel, copper, brass, bronze or any other suitable material to which a deposit of metal applied electrically or by well-known spray methods, will adhere firmly. Upon this foundation web of netting, a continuous surface of metal is formed bridging the openings or mesh between the wires, and thus making a sheet of metal supported upon and firmly adherent to the wire web. The metal deposited electrically or otherwise, may be either copper or nickel or any other suitable metal that is capable of being formed on the web in a smooth even film, but the metals mentioned, or a combination of the two, are preferred, on account of the ease with which they may be deposited and because of the strength of the metallic film so formed.

The invention accordingly comprises the features of construction, the steps and the sequence of steps which are exemplified in the structures hereinafter described and the scope of the application of which will be indicated in the following claims.

In the accompanying drawings showing one or more of various possible embodiments of this invention,

Figure 1 is a side elevation of apparatus for depositing a layer of metal on the web,

after the web has first received a preliminary treatment with filling material, such as varnish;

Fig. 2 is a similar view of apparatus for 55 depositing a layer of metal on the web, after the web has received a preliminary treatment with a suitable paste;

Fig. 3 is a similar view of apparatus for 60 forming a surface on the web by means of a thin sheet of metal or foil, and locking the sheet of metal or foil to the web by electro-deposition, and

Fig. 4 is a similar view of apparatus for 65 forming a coating or layer of metal on the web, by means of a spray of metal.

Similar reference characters indicate corresponding parts throughout the several views of the drawings.

First method.—A coating of varnish or 70 collodion or any other suitable filling material of similar nature, which is insoluble in water, is applied to the wire mesh in such manner that it closes all the openings between the wires over substantially the entire surface area of the web. After this coating is applied, one of the surfaces is cleaned, exposing the wires, and a conducting material is buffed or rubbed into the surface of the filling material. This conducting material may be either a metallic powder 75 or graphite, or any other suitable material, which can be applied to the surface of the varnish or coating, and is a conductor of electricity. The web or wire net is then 80 placed in or run through an electroplating bath and the entire surface is plated with 85 the metal to be deposited.

Fig. 1 shows a plating bath A having a suitable electrolyte B and an electrode C. 90 The wire mesh M properly treated as described, is run through the bath from the roll D, over the roller E, to the rewinding roll F. The roller E forms the other terminal of the circuit, and a film or coating of 95 metal is deposited on the prepared side of the wire mesh.

Second method.—Instead of using varnish, a paste made of finely divided metals mixed with a simple binder, may be spread 100 smoothly over the mesh, either by spreading the same under moderate pressure, or by

passing the wire mesh and the filling material between rolls. One of the surfaces is then cleaned to insure that the wires will be exposed, and the webbing thus filled is passed through an electroplating bath, as described.

In Fig. 2, G and H represent rolls between which the wire mesh M' passes, and J represents a nozzle or pot for feeding the paste to the mesh between the rolls. The mesh passes over a roller K and around a drum L to the rewinding roll O. In so passing, the mesh dips into the electroplating bath B, as in Fig. 1.

15 In either method illustrated in Figs. 1 and 2, after a continuous metallic surface is secured by depositing a metal over the surface of the filled web, the plated web is then passed through a suitable solution, 20 which will dissolve the varnish or collodion or the binding material contained in the metallic paste, and when the filling material has been entirely removed, the web and its surface are then in condition to be used; or 25 the material may be strengthened by again passing the web through a plating bath and depositing another coating of metal on the back or reverse side opposite to that which received the first deposit; or an additional film may be deposited on both sides 30 in this second operation, but such second operation is not essential, except where it is desired to reinforce and strengthen the surface originally produced.

35 *Third method.*—The metallic surface may also be obtained by firmly pressing upon the surface of the web a thin sheet of metal, such as tinfoil or silver foil or any other very thin metallic film of suitable metal, 40 and then locking this film to the web by depositing metal on the reverse side, thereby locking the surface of film firmly to the wires.

In Fig. 3, the web M² is shown passing 45 from the roll D, over the roller E, through the bath B, to the rewinding roll F. The thin sheet of metal or foil P passes from the roll Q over the roller E, between the surface of said roller and the web M², and the 50 rewinding roll F takes up both the web M² and the foil P. The web M² is placed under sufficient tension to press the foil or thin sheet of metal P tightly against the same, and the electro deposit of metal from the 55 bath B firmly locks the foil to the web.

As a modification of these methods, the metallic surface film may be formed by spraying heated metal upon the treated web, as shown in Fig. 4, in which the web M 60 after preliminary treatment with varnish or the like, or metallic paste, or with thin sheet metal or foil from reel Q pressed against the same is passed over a roller E or over a table, and metal is sprayed onto 65 the web from a suitable sprayer R in a

well-known manner, thus forming the continuous metallic surface on the web, as before.

The color of the surface deposit may be controlled by controlling the metal deposited, or the rate of deposition, or by depositing a combination of more than one metal, as desired.

70 *Fourth method.*—My invention also contemplates a thermo process of soldering, brazing or welding the wire mesh to a thin sheet of metal, whether that thin sheet of metal is first produced by electro-deposition or by some other method of making sheet metal. By this means the wire mesh may 75 be attached to and incorporated with a thin sheet copper surface, for instance, as a reinforcing backing, although other metals may be used for the thin sheet surface instead of copper.

80 One example of this modified method of attaching the mesh to the thin sheet is by tinning the two together by any usual method, such as used in depositing a coating of tin or silver on glass in producing 85 mirror surfaces by silvering, as for instance, by means of a reducible salt of tin incorporated with a volatile oil. A web of copper mesh and a thin sheet of copper may be securely attached together in this way. They 90 should preferably first be thoroughly cleaned, as by scouring, washing or by acid liquids, and heated almost up to the melting point of tin by suitable means, to which 95 heated surfaces the tinning materials are 100 supplied.

The covering material produced by the herein-described method, has the advantages of being thin, strong and non-combustible. It can be produced either in continuous 105 lengths or in continuous sheets of any reasonably desired area. The wire mesh provides a strong support which is strengthened by the material deposited, which is firmly attached to and homogeneously incorporated with the material of the wires.

110 In view of the above it will be seen that the several objects of this invention are achieved, and other advantageous results attained.

115 As various possible embodiments might be made of the above invention and as various changes might be made in the embodiments above set forth, it is to be understood that all matter herein set forth or shown in the accompanying drawings is to be interpreted as illustrative and not in a limiting sense.

I claim and desire to obtain by Letters Patent the following:

120 1. The method of making sheet material, which consists in mechanically applying a metallic surface directly to a wire mesh or web and locking the same in position by applying and incorporating metal upon the 125 130

reverse side in contact with and attached to both the metallic surface and the wires of the mesh.

2. The method of making sheet material, which consists in mechanically applying a metallic surface directly to a wire mesh or web and locking the same in position by spraying heated metal upon the reverse side of the web, thereby incorporating the metal

with both the metallic surface and the wires 10 of the web.

In testimony whereof I have signed this specification in the presence of two subscribing witnesses.

WALTER G. CLARK.
